RAILWAY SWITCH OPERATING APPARATUS

John W. Logan, Jr., Forest Hills, Pa., assignor to
The Union Switch & Signal Company, Swiss-
vale, Pa., a corporation of Pennsylvania

Application May 17, 1944, Serial No. 535,914

8 Claims. (Cl. 246—291)

My invention relates to railway switch operating apparatus, and particularly to switch operating apparatus for switches of the so-called spring return type in which the switch points set in a given position relative to the main rails of the track are adapted to yield laterally against the action of spring means when a train trails the switch, and to be retarded in the return movement to the normal set position under the action of the spring return means by dash-pot or buffer mechanism.

More particularly, my present invention relates to railway switch operating apparatus in which the spring means and dash-pot mechanism are combined into a unitary biasing and buffering device similar to that described in Letters Patent of the United States No. 2,191,246, granted to O. W. Anderson on February 20, 1940, for Railway switch piston and cylinder device, the said device being disposed between the switch and the switch operating mechanism.

In switch operating apparatus of the type described there is a sudden reversal in the direction of loading on the biasing and buffering device following the passage of each truck on a car trailing the switch, and this sudden reversal causes a sudden shock to be transmitted through the biasing and buffering device to the operating parts of the switch operating mechanism. Inasmuch as some mechanical clearance is necessary between the operating parts of the switch operating mechanism, this sudden shock causes a hammering action which produces wear on all parts involved including the track switch itself.

One object of my present invention is to provide means whereby the shock due to the sudden reversal in the direction of the loading on the biasing and buffering device is prevented from reaching the working parts of the switch operating mechanism.

According to my present invention, I accomplish the above outlined object by providing adjustable stop means which cooperates with the casing of the biasing and buffering device in such manner that any sudden shocks which are transmitted to the biasing and buffering device due to reversals in the direction of loading of this device will be absorbed by the stop means, and will not therefore be transmitted to the working parts of the switch operating mechanism. The provision of this stop means also reduces wear on the switch points because of the resulting reduction in the amount of motion which can take place when the loading on the buffering device becomes reversed.

The present invention is directed to subject

matter which is closely related to that disclosed and claimed in an application for Letters Patent of the United States, Serial No. 522,098, filed by Herbert L. Bone on February 12, 1944, for Railway switch operating apparatus, which application is of common ownership with the present application.

Other objects and characteristic features of my invention will become apparent as the description proceeds.

I shall describe two forms of railway switch operating apparatus embodying my invention, and shall then point out the novel features thereof in claims.

15 In the accompanying drawings, Fig. 1 is a top plan view showing a spring switch controlled by a switch operating mechanism constructed in accordance with my invention. Fig. 2 is an enlarged top plan view of a portion of the mechanism shown in Fig. 1. Fig. 3 is a detail view taken substantially on the line III—III of Fig. 2. Fig. 4 is an end view, partly sectional, of the portion of the mechanism shown in Fig. 2. Fig. 5 is a view similar to Fig. 4 showing a modified form 20 of my invention.

Similar reference characters refer to similar parts in all four views.

Referring first to Fig. 1, the reference character A designates a railway switch comprising, as usual, two fixed rails 1 and 1a and two movable rails or switch points 2 and 2a. The fixed rails 1 and 1a are laid on tie plates 3 and are secured to crossties 4 in the usual manner. The movable rails 2 and 2a are fastened together by a front rod 5, a head rod 6, a bridie rod 7, and a tie rod 8, and may be moved into a normal or a reverse position by means of a switch operating mechanism B which is connected with the head rod 6 through the medium of a combined biasing and buffering device D. When the switch occupies its normal position in which position it is shown in Fig. 1, the movable rail 2 engages the fixed rail 1, and the movable rail 2a is spaced a slight distance from the fixed rail 1a. When the switch 35 is reversed, however, the movable rail 2a then engages the fixed rail 1a, and the movable rail 2 is spaced from the fixed rail 1.

The combined biasing and buffering device D is similar in all respects to that described in Letters 40 Patent of the United States No. 2,191,246 referred to hereinbefore, and it is believed, therefore, that for purposes of the present disclosure it is sufficient to point out that this device comprises a cylindrical housing 10 which is operatively connected at one end with the switch operating

crank 11 of the switch operating mechanism B through the medium of an integral lug 10a and a pivot pin 12, and which is provided at the other end with a reciprocable operating rod 13. The operating rod 13 is slidably supported intermediate its ends in a supporting bracket 14 secured to two adjacent ties 4, and is adjustably connected at its free end to the head rod 6 through the medium of the usual switch basket 9. The operating rod 13 is biased by suitable spring means enclosed within the housing 10, to an intermediate position relative to the housing in such manner that movement of the operating rod in either direction from its intermediate position will cause the spring means to become compressed and exert a yieldable force on the operating rod which tends to return it to its intermediate position relative to the housing. The operating rod is also connected within the housing 10 with double acting buffing means which become effective upon movement of the operating rod by the spring means to limit the rate of movement of the operating rod to a predetermined controlled rate which is sufficiently slow to prevent slapping of the switch points between the passage of successive wheels or trucks of a car or train trailing the switch, as will appear more fully hereinafter.

The switch operating mechanism B may be of any suitable type, but as here shown it is similar to that described and claimed in Letters Patent of the United States No. 2,235,031, granted to Kenneth J. J. McGowan on March 18, 1941, for Railway switch operating apparatus. For a clear understanding of my present invention it is sufficient to point out that this mechanism comprises a suitable casing 15 containing a switch actuating shaft 16 provided at its lower end with the switch operating crank 11 mentioned above. This mechanism also comprises a hand throw lever 17 which is rotatable between two extreme positions, and which is operatively connected through the medium of a pinion, a rack, and an escapement crank not shown, with the switch operating shaft 16 in such manner that rotation of the hand throw lever between its two extreme positions will rotate the switch operating crank 16 between its two extreme positions. The mechanism further comprises a locking plunger 18 which is biased to a locking position, and which in its locking position enters a notch 19 in a lock rod L secured to the front rod 5 of the switch A to lock the switch in its normal extreme position, as shown. The locking plunger is operatively connected with the hand throw lever 17 through the medium of the previously mentioned motion plate in such manner that when the hand throw lever is operated in the direction to move the switch away from its normal extreme position, the locking plunger will be moved to an unlocking position in which it is completely withdrawn from the notch 19 prior to any movement of the switch points. The locking plunger is also operatively connected by means of suitable linkage 20 with the tie rod 8. When a train starts to trail the switch, this latter linkage is mechanically actuated through the medium of the tie rod 8 in a manner which causes it to move the locking plunger to its unlocking position before sufficient force is exerted on the switch points by the train to overcome the biasing force of the device D.

The operation as a whole of the portion of the apparatus thus far described is as follows: When the hand throw lever 17 is rotated to its normal extreme position, as shown, the buffing device D

is moved to the left, by virtue of its connection to the switch operating crank 11, to its normal extreme position in which it acts to bias the switch points to their normal positions, and if 5 the switch points then occupy their normal positions, as will be the case if no train is trailing the switch and all parts are in proper working order, the locking plunger 18 will enter the notch 19 in the lock rod L and will lock the switch points in their normal extreme positions.

When it is desired to reverse the switch points, the hand throw lever 17 is rotated from the extreme position shown to its opposite extreme position. As was pointed out hereinbefore, this movement of the hand throw lever will first act to withdraw the locking plunger 18 from the notch 19 in the lock rod L, and will then act to move the switch operating crank 11 from its normal to its reverse extreme position. The movement of the crank 11 to its reverse extreme position, in turn, will move the device D bodily toward the track to its reverse extreme position, and will thus cause it to move the switch points to and yieldably hold them in their reverse extreme positions.

After the switch has been moved to its reverse extreme position in the manner just described it can be restored to its normal extreme position by restoring the hand throw lever to its normal extreme position. The subsequent movements of the parts under these conditions is just the reverse of those just described, and will be obvious from the foregoing and from an inspection of the drawings without further detailed description.

When a train trails the switch, as the leading wheels of the train roll along the fixed rail 1 and the movable rail 2a, the movable rails 2 and 2a will be forced over laterally, but before a sufficient force is developed to overcome the opposing force exerted by the device D and cause the point of the movable rail 2 to move out of engagement with the fixed rail 1, the movable rails being somewhat resilient will become bent, so that with a standard split switch sufficient lateral movement of the rails will take place to cause the linkage 20 to move the locking plunger 18 to its unlocking position. As a result, when the leading wheels of the train have reached the positions in which a sufficient force is developed to cause the point of the movable rail 2 to move out of engagement with the fixed rail 1, the switch points will be unlocked, and the switch points will therefore be forced open in opposition to the biasing force exerted by the device D in exactly the same manner as would be the case if no point lock were provided, and the device B will perform its further function of preventing the rails from returning to their original set positions after the passage of each wheel through them. When the train which is trailing the switch has completely passed the switch, the movable rails will slowly return to their normal positions under the bias of the spring means of the device D and against the retarding force exerted by the buffing means of the device D. When the rails reach their full normal positions, the locking plunger will return to its locking position due to its associated biasing means, and all parts will be restored to the positions shown.

I have found that with the switch points biased to their normal positions by means of the device D in the manner described above, each time the truck of a car which is trailing the switch clears the switch points, a slight amount of return movement of the switch points, usually about $\frac{1}{4}$ inch,

takes place before the buffing action of the device D becomes effective, and as a result when the buffing action does become effective, a certain amount of momentum of the points, and of the parts of the buffing device which move with the points, has been built up due in part to the action of the spring biasing means of the device, and in part to the fact that since the points when trailed are moved past their mid stroke positions, the inherent resiliency of the points sets up a force which tends to return the points to their mid stroke positions. Consequently, when the buffing action of the device D does become effective, the device D momentarily loses its characteristics as a flexible member and acts as a rigid link. As a result, unless suitable means are provided to prevent it, the momentum of the parts will cause a sudden shock to be transmitted to the switch operating crank 11, and hence to the operating parts of the mechanism B, and since there is necessarily a certain amount of clearance between these parts, wear on all parts including the track switch itself is greatly accelerated. This is undesirable and according to my present invention I provide stop means which I shall now describe whereby the shock due to the sudden reversal of the load in the device D under the conditions described above is prevented from reaching any of the working parts of the mechanism.

Referring now also to Figs. 2, 3 and 4, this stop means comprises a stop stud 21 secured as by riveting to a supporting member 22 which extends transversely of the device D adjacent the end nearest the mechanism B. As shown, the member 22 is in the form of an angle bar, and rests at its ends on upright supports 23 secured to two of the adjacent ties 4 by means of bolts 25 or their equivalent. The member 22 is adjustably secured to the supports 23 in an adjusted position by means of tap bolts 26 which extend through slots 27 in the one flange of the member and are screwed into threaded holes 28 provided in the supports. To facilitate adjusting the member 22 relative to the supports, horizontal studs 29 are riveted to the vertical flange of the member and extend with clearance through transversely extending holes 30 provided in the supports 23. Mounted on the studs on opposite sides of the vertical flange of the member 22 are adjusting nuts 31.

With the parts of the stop means constructed in this manner it will be obvious that when the tap bolts 26 are loosened, the slots 27 permit the supporting member 22 to be moved toward or away from the mechanism B to positions determined by the positions of the nuts. The member 22 is so adjusted that when the parts of the switch A and switch operating mechanism B occupy their normal positions as shown in Fig. 1, the stud 21 will just touch the end face of the device D at the end nearest the mechanism B. The point at which the stud touches the end face of the device is not important but as shown the point of contact of the stud with the end face is near the upper edge of the end face directly above its center line, this point being disposed between the adjacent bolts or studs (not shown) which secure the head to the tubular casing of the device. With the parts positioned and adjusted in this manner, any force which is exerted on the device D tending to move it bodily toward the mechanism B when the mechanism B is in its normal position will be transmitted directly from the device to the stop stud 21, rather than to the working parts of the mechanism through the crank 11. It follows, therefore,

that when a train trails the switch, the stop means will act to effectively prevent wear on the working parts of the mechanism B due to the momentary reversal in the force which is exerted on the device D each time a wheel of a train which is trailing the switch clears the switch points, whereby the life of the switch operating apparatus is greatly lengthened.

It should be noted that since the adjustable stop means only engages the device D when the parts are in their normal positions, the stop means does not interfere at any time with the normal operation of the parts.

It should also be noted while as illustrated in Fig. 1, I have shown stop means embodying my invention applied to a normally closed point layout, it can also be applied to a normally open point layout by merely moving the stop means to the opposite end of the device and adjusting the member 22 so that with the parts in their normal positions the stop stud 21 will just touch the end face of the then adjacent head of the device.

Referring now to Fig. 5, I have here shown a modified form of stop means which can be used in place of that shown in the preceding views when the device D is used in combination with certain types of switch operating mechanisms. As here shown, the stop means comprises a stop screw 32 adjustably screwed into a boss 10b provided in the one head of the device D, and so adjusted that when the parts are all in their normal positions the head of the stop means will engage a relatively strong fixed part of the mechanism such as the side edge of the base flange of the casing. The stop screw is arranged to be locked in its adjusted position by means of a lock nut 33.

It will be obvious that with the stop screw 32 adjusted and arranged as just described, any force which is exerted on the device D tending to move it bodily toward the mechanism B when the operating parts of the mechanism B are in their normal positions will be transmitted through the stop stud to the casing of the mechanism rather than to the operating parts of the mechanism through the crank 11. It follows, therefore, that the stop means shown in Fig. 5 will act to prevent wear in the same manner as the stop means shown in Figs. 1 to 4, inclusive.

Although I have herein shown and described only two forms of railway switch operating apparatus embodying my invention, it is understood that various changes and modifications may be made therein within the scope of the appended claims without departing from the spirit and scope of my invention.

Having thus described my invention, what I claim is:

1. The combination with a spring switch connected with a switch operating mechanism through a device which acts to yieldably resist movement of the switch points away from a set position and to retard the return movement of the points to their set position when a train trails the switch, of stop means interposed between a portion of the casing of said device that is non-yieldably connected to said switch operating mechanism and a fixed member and effective upon a reversal in the direction of the force applied to said device while a train is trailing the switch to prevent the transmission of shocks through said device to the operating parts of said mechanism.
2. The combination with a spring switch con-

nnected with a switch operating mechanism through a combined biasing and buffing device which acts to yieldably resist movement of the switch points away from a set position and to retard the return movement of the switch points to their set position when a train trails the switch, of stop means for preventing the transmission of shocks through said device to said operating mechanism after the passage of each wheel or truck of a train trailing the switch, said stop means comprising a supporting member extending transversely of said device adjacent one end of said device and adjustably supported at its ends on fixed supports for movement toward and away from said device, and a stop member secured to said supporting member for cooperation with said one end of said device, said supporting member being adjusted so that any movement of said device due to the transmission of sudden shocks thereto following the passage of a wheel or truck through the switch will be prevented by engagement of said device with said stop member.

3. The combination with a spring switch connected with a switch operating mechanism through a combined biasing and buffing device which acts to yieldably resist movement of the switch points away from a set position and to retard the return movement of the switch points to their set position when a train trails the switch, of stop means for preventing the transmission of shocks through said device to said operating mechanism after the passage of each wheel or truck of a train trailing the switch, said stop means comprising a supporting member extending transversely of said device adjacent one end of said device and adjustably supported at its ends on two adjacent ties for movement toward and away from said device, and a stop member secured to said supporting member for cooperation with said one end of said device, said supporting member being adjusted so that any movement of said device due to the transmission of shocks thereto following the passage of a wheel or truck through the switch will be prevented by engagement of said device with said stop member.

4. The combination with a spring switch connected with a switch operating mechanism through a combined biasing and buffing device which acts to yieldably resist movement of the switch points away from a set position and to retard the return movement of the switch points to their set position when a train trails the switch, of stop means for preventing the transmission of sudden shocks through said device to said operating mechanism after the passage of each wheel or truck of a train trailing the switch, said stop means comprising a pair of supports secured to two adjacent ties at one end of said device, a supporting member resting at its ends on said supports and adjustably secured thereto by means of tap bolts passing through slots provided in said member and screwed into tapped holes provided in said supports, means for adjusting said supporting member relative to said supports comprising studs secured to said supporting member and extending through clearance holes formed in said supports and provided on opposite sides of said supports with adjusting nuts, and a stop member secured to said supporting member and cooperating with the casing of said device, said supporting member being adjusted so that any movement of said device due to the transmission of shocks thereto when

the switch points start to return to their set positions will be prevented by engagement of said device with said stop member.

5. The combination with a spring switch connected with the operating crank of a switch operating mechanism through a combined biasing and buffing device including a casing pivotally attached at one end to said crank and movable toward and away from the switch in response to movement of said crank and an operating rod slidably supported in the other end of said casing and operatively connected at its free end with said switch, said device acting to yieldably resist movement of the switch points away from a set position and to retard the return movement of the switch points to their set position when a train trails the switch, of stop means for preventing the transmission of shock through said device to the operating parts of said mechanism each time the switch points start to return to their set position, said stop means comprising a supporting member extending transversely of said device at the end which is connected to said crank, means for securing said supporting member in a position which is adjustable relative to said device, and a stop stud secured to said supporting member, the position of said supporting member relative to said device being so adjusted that any movement of said device due to the transmission of shocks thereto each time the switch points start to return to their set position from a displaced position will be prevented by engagement of said stud with the end of said casing.

35 6. The combination with a spring switch connected with a switch operating mechanism through a device which acts to yieldably resist movement of the switch points away from a set position and to retard the return movement of the points to their set position when a train trails the switch of an adjustable stop screw attached to a portion of the casing of said device that is non-resiliently connected to said mechanism and adjusted to cooperate with a fixed part of said mechanism upon a reversal in the direction of the force applied to said device while a train is trailing the switch to prevent the transmission of shock through said device to the operating parts of said mechanism.

50 7. The combination with a spring switch connected with a switch operating mechanism through a device which acts to yieldably resist movement of the switch points away from a set position and to retard the return movement of the points to their set position when a train trails the switch of adjustable stop means interposed between a portion of the casing of said device that is non-resiliently connected to said mechanism and a fixed part of said mechanism and adjusted to act upon a reversal in the direction of the force applied to said device while a train is trailing the switch to prevent the transmission of shocks through said device to the operating parts of said mechanism.

60 8. The combination with a spring switch connected with the operating crank of a switch operating mechanism through a combined biasing and buffing device including a casing pivotally attached at one end to said crank and movable toward and away from the switch in response to movement of said crank and an operating rod slidably supported in the other end of said casing and operatively connected at its free end with said switch, said device acting to yieldably resist movement of the switch points away from

a set position and to retard the return movement of the switch points to their set position when a train trails the switch, of stop means for preventing the transmission of shock through said device to the operating parts of said mechanism each time the switch points start to return to their set position, said stop means comprising an adjustable stop screw attached to said

one end of said casing and adjusted to cooperate with a fixed part of said mechanism upon a reversal in the direction of the force applied to said device while a train is trailing the switch to prevent the transmission of shock through said device to the operating parts of said mechanism.

JOHN W. LOGAN, JR.
